UNITED STATES PATENT OFFICE.

JOHN IRVING, OF WARREN, MASSACHUSETTS.

CENTERING DEVICE.

SPECIFICATION forming part of Letters Patent No. 352,693, dated November 16, 1886.

Application filed February 26, 1886. Serial No. 193,338. (No model.)

To all whom it may concern:

Be it known that I, JOHN IRVING, of Warren, in the county of Worcester and State of Massachusetts, have invented a new and Improved Centering Device, of which the following is a full, clear, and exact description.

The object of my invention is to provide a new and improved device for centering rods, shafts, cylinders, &c., and for laying out equidistant centers for holes in a circle at a given radius from the center.

The invention consists of a frame provided with two movable external and internal caliper heads, each attached to a rack which is in gear with a central pinion of an index and of a graduated radius-bar.

The invention also consists of various parts and details and combinations of the same, hereinafter more fully set forth, and pointed out in the claims.

Reference is to be had to the accompanying drawings, forming a part of this specification, in which similar letters of reference indicate corresponding parts in all the figures.

Figure 1 is a plan view of my improvements, parts being broken out and others in section. Fig. 2 is a longitudinal vertical section of the same on the line *xx* in Fig. 1. Fig. 3 is a vertical cross-section of the same on the line *yy* of Fig. 1. Fig. 4 is a plan view of the same, with index and graduated radius-bar attached for laying out equidistant centers in a circle; and Fig. 5 is a vertical cross section of the same on the line *zz* of Fig. 4.

The main frame *A* of the centering device consists of the bottom plate, *A'*, having the end pieces, *A²* and *A³*, and the side pieces, *A⁴* and *A⁵*, which form the recesses *A⁶* and *A⁷*, and of the top plate, *A⁸*, secured at the end pieces, *A²* and *A³*, to the bottom plate, *A'*. In the center of the frame *A* is secured the pin *B*, having a central aperture, *B'*, and on the pin *B* is placed and turning loosely on the same, the pinion *C*, which meshes on its sides with the racks *D* and *D'*, sliding between the top plate, *A⁸*, and the bottom plate, *A'*, and resting partly against the side pieces, *A⁴* and *A⁵*. To one outer end of each of the racks *D* and *D'* is secured a caliper head, *E*, in such a manner that they are in opposite directions from the central pin, *B*, and equidistant from the center of the same. The caliper heads *E* are re-

cessed and fit over and slide on the frame *A*. The bottom parts, *E'*, of the caliper heads *E* are provided on each side with beveled edges *E'*, which form the external and internal caliper edges of the devices. The upper parts, *E²*, of the caliper heads *E* are each provided with a short handle, *E'*, by which the caliper head may be easily moved on the frame *A*. They also act as calipers for small holes. To the side part, *E⁵*, of each caliper head, which is secured to rack *D* or *D'*, is fastened a short arm, *F*, having a recess, *F'*, in which slides a bar, *F²*, having a semicircular recess on its inner end and provided on its outer end with a knob, *F³*. The side parts, *E⁵*, of the caliper heads *E* and the short arms *F* slide in the recesses *A⁶* and *A⁷*, formed by the side pieces, *A⁴* and *A⁵*, of the frame *A*. Attached to the bottom plate, *A'*, and placed on the opposite sides of the pinion *C*, are the lugs *G* and *G'*, to each of which and to the end pieces, *A²* and *A³*, of the frame *A* are secured, respectively, the rods *H* and *H'*, around each of which is placed the coiled spring *H'*.

This device is used as follows: The center of a cylinder, for instance, is obtained by sliding the caliper heads *E* on the frame *A* so that the distance between the outer edges of the bottom parts, *E'*, is a trifle larger than the inside diameter of the cylinder to be centered, after which the bars *F²* are pressed inwardly until their recessed inner ends fit over the rods *H* and *H'*. The caliper heads are then moved inwardly toward each other until the outer edges of the bottom parts, *E'*, rest against the inner face of the cylinder, as shown in Figs. 1 and 2. The springs *H'* are compressed by the inward motion of the caliper heads *E* by means of the bar *F²*, and exert now an outward pressure against the said calipers and hold the same in place on the inner face of the cylinder. It will also be seen that when one caliper head *E* is moved to or from the pin *B* the other caliper head is caused to slide the same distance to or from the pin *B*. A small plug, *I*, having a central recess, *I'*, on the top, is placed in the aperture *B'* of the pin *B*. The recess *I'* is then exactly in the center of the cylinder to be centered, and forms a resting point for the leg of the compass with which the operator performs the work required.

For centering rods or shafts the inner edges

of the bottom parts, E', are placed against the circumference of the work to be centered in a similar manner, as above described. Instead of the plug I, a centering-plug, J, (shown in Fig. 5,) is inserted from above into the aperture B' of the pin B, the point of the said center-plug J being the center of the rod or shaft to be operated on. A slight tap with a hammer on top of the center-plug J leaves a center dent on the rod or shaft, the pin acting as guide during the operation.

For laying out equidistant centers for holes in a circle, I employ an index, K, having the usual arrangement of dents, K', or apertures on the top plate, K². To the latter is attached on its bottom a graduated radius-bar, L, on which slides the center-plug holder M, which can be securely held at any desired point on the radius-bar L by the set-screw M'. The plug-holder M is provided with an offset, M², having a vertical aperture in which the centering-plug J is inserted for marking the given number of centers in a circle. The index K swings loosely on a recessed shank, N, provided on its lower end with a screw-threaded pin, N', which is placed in the aperture B' of the pin B and securely held to the frame A by the nut N². On the upper end of the shank N is formed a collar, N³, from which projects a screw-threaded pin, N⁴, upward, on which is placed the arm O, having a slot, O', and a set-screw, O², and can be secured on the pin N⁴ and the collar N³ by the nut N⁵.

This device is used as follows: The frame A is placed across the work to be operated on and the caliper head E adjusted against the inner or outer edges of the work, as before described, whereby the center of the object is obtained in the center of the pin B. The index K and its radius-bar L are placed on the frame A by inserting the pin N' into the aperture B' of the pin B and fastening the shank N to the frame A by tightening the nut N², as shown in Fig. 5. The plug-holder is then moved to a point on the graduated radius-bar L which is to be the radius of the circle in which the centers are to be marked. The arm O is then moved on the pin N⁴ until the point of the set-screw O² is in line with the circle of the respective dents K' on the index-plate K², which are to be marked, and the arm O is then fastened to the collar N³ by the nut N⁵. The index-plate K² and its radius-bar L are then turned until a dent is under the point of the set-screw O², which is then screwed down into the respective dent K', whereby the index-plate K² and its radius-bar L are held in place. The center-plug J is then inserted into the aperture M³ on the plug-holder M, and the first center is then marked. The set-screw O² is then screwed upward to set the index-plate K² free, which is then turned until the next dent K' comes under the point of the set-screw O², which is screwed downward to fasten the index-plate K² again to the arm O, and the

above-described operation is repeated until all the centers on the work are marked.

Having thus fully described my invention, I claim as new and desire to secure by Letters Patent—

1. In a centering device, the combination of a frame with internal and external caliper heads attached to racks which mesh into a pinion turning on a central hollow pin, with stationary rods attached to the frame, with springs placed on the said rods, and with sliding bars fitted to the calipers to compress the said springs, substantially as shown and described.

2. In a centering device, a frame on which slide internal and external caliper heads attached to racks which mesh into a pinion turning on a hollow pin, and provided with stationary rods around which are placed springs which are compressed by sliding bars, in combination with an index and graduated radius-bar turning on a shank provided with an arm and set-screw, the said shank being secured in the center of the frame, substantially as shown and described.

3. In a centering device, the frame A, the pin B, having an aperture, B', the pinion C, the rods H, and the springs H', in combination with the racks D and D', and the caliper heads, substantially as shown and described.

4. In a centering device, the frame A, the pin B, the pinion C, the rods H, and the spring H', in combination with the racks D and D', the caliper heads E, having the beveled inner and outer edges, E², and the sliding bar F', substantially as shown and described.

5. In a centering device, the frame A, the pin B, having the aperture B', the pinion C, the racks D and D', the caliper heads E E, the rods H H, and the springs H', in combination with the index K, provided with a graduated radius-bar, the shank N, and the adjustable arm O, substantially as shown and described.

6. In a centering device, the pinion C, the racks D and D', the caliper heads E, provided with the beveled edges E², the short arm F, and the sliding bar F², in combination with the rods H, secured in the frame A, and the springs H', substantially as shown and described.

7. In a centering device, the frame, the pin B, the pinion C, the racks D and D', the caliper heads E, the rods H, the springs H', the shank N, and the adjustable arm O, provided with the set-screw O², in combination with the index-plate K², the graduated radius-bar L, and the center-plug holder M, substantially as shown and described.

JOHN IRVING.
